UNITED STATES PATENT OFFICE

131,625

DESIGN FOR A COMBINATION BOOK AND MAGAZINE CABINET, RADIO, LAMP, AND LAMP SUPPORT

Mitchell Reid Wright, Covington, Ga.

Application July 2, 1941, Serial No. 101,861

Term of patent 3½ years

To all whom it may concern:

Be it known, that I, Mitchell R. Wright, a citizen of the United States, residing at Covington, in the county of Newton and State of Georgia, have invented a new, original, and ornamental Design for a Combination Book and Magazine Cabinet, Radio, Lamp, and Lamp Support, of which the following is a specification, reference being had to the accompanying drawing, forming part thereof.

Fig. 1 is a perspective view of the combination book and magazine cabinet, radio, lamp, and lamp support, showing my design; and

Fig. 2 is a side elevational view thereof.

The article comprising the book and magazine cabinet includes the shelving, the drawer, the table top and the ash tray near the center of the table top.

I claim:

The ornamental design for a combination book and magazine cabinet, radio, lamp, and lamp support, as shown and described.

MITCHELL REID WRIGHT.
